United States Patent Office.

JOSEPH W. WATTLES, OF CANTON, MASSACHUSETTS.

Letters Patent No. 98,133, dated December 21, 1869.

IMPROVEMENT IN LUBRICATORS FOR THE BOLSTERS OF VERTICAL SHAFTS.

The Schedule referred to in these Letters Patent and making part of the same.

To all persons to whom these presents may come:

Be it known that I, JOSEPH W. WATTLES, of Canton, of the county of Norfolk, and State of Massachusetts, have made a new and useful invention, having reference to the lubrication of bolsters and steps of the spindles of spinning-machines; and I do hereby declare the same to be fully described in the following specification, and represented in the accompanying drawing, which represents a vertical section of a spindle, and its bolster and step, as provided with my invention.

In carrying out my invention, I extend from the bolster down by the whirl, and to the step, a conduit or tube, so applied to the bolster and step as to convey oil from the interior bearing of the bolster; or an intercepting chamber, *a*, formed therein, down into the step, the whole being as hereinafter explained.

In the drawings—

A denotes a spindle, *B* the bolster, and *C* the step, the whirl being shown at *E*.

The conduit or pipe leading from the bolster to the step is shown at *D*, it being made to open out of an intercepting chamber, *a*, formed in the bolster and around the spindle.

At its foot, the tube opens into the spindle-step, which is also provided with an oil-chamber.

The top of the bolster is concave, to receive the oil.

The surplus oil of the bolster will flow down through the tube, and into the step. In case the bolster be provided with the intercepting chamber, such oil will first be caught thereby.

My improvement renders it necessary to apply oil to the bolster only, and saves the necessity of applying it also to the step. It prevents much if not all waste oil from running down from the bolster and upon the spindle and whirl. It effects a very considerable saving of oil, over what would be required for the separate lubrication of the bolster and step in the ordinary way.

In order that the conduit may be readily applied to and removed from the step and bolster, to facilitate the removal either of the latter from their supporting-rails, I provide the step, as well as the bolster, with a

hole or passage, leading laterally out of it, such being as shown at *b* and *c*, for the reception of the end of the conduit, such conduit being applied to the step and bolster by being sprung into said holes or passages.

From the above it will be seen, that by the arrangement of the tube or conduit *D*, it bows around the whirl, so as not to interfere with it, the said whirl being situated between the step and the bolster.

I am aware of the lubricator of Lesfe, the specification and drawings of which were filed in the Patent Office on December 9, 1865, and, consequently, make no claim to such. It is somewhat analogous to my invention, though very different therefrom, both in construction and mode of operation. It applies to a single tubular bearing of a shaft. Its tube is not arranged as mine is, viz, so as to bow around the whirl or driving-pulley, and lead from one bearing, over such whirl, to a separate and distinct step arranged below it. It simply has an oil-chamber at the top of the bearing, with no part of the bearing extended above such oil-chamber, as is the case with my bolster.

The bearing of Lesfe is continuous to the step, and opens communication therewith, so that oil may flow upward from the step, through the endless bearing, and into the intercepting chamber, and thence out of such through its discharge-tube; but with my bolster and step, no such action of the oil can take place.

What I claim, therefore, as my invention in spinning-machines, is—

The arrangement of the conduit *D*, relatively to the bolster, the whirl, and the step of the spindle, the bolster being above and the step being below the whirl, the whole being substantially in manner as specified.

Also, the bolster, as made with the oil-intercepting chamber *a*, and the hole *b* leading laterally out of the same, and with the spindle-bearing extended both above and below the intercepting-chamber, the whole being as and for the purpose specified.

JOSEPH W. WATTLES.
